UNITED STATES PATENT OFFICE.

WILLIAM W. LOWREY, OF STATEN ISLAND, NEW YORK.

DESIGN FOR A BOTTLE.

SPECIFICATION forming part of Design No. 24,579, dated August 20, 1895.

Application filed July 9, 1895. Serial No. 555,442. Term of patent 3½ years.

To all whom it may concern:

Be it known that I, WILLIAM W. LOWREY, a citizen of the United States of America, and a resident of Staten Island, Richmond county, 5 State of New York, have invented a new and useful Design for a Glass Bottle, of which the following is a specification.

In the drawings, Figure 1 represents a front elevation of a glass bottle, showing my design. 10 Fig. 2 represents a horizontal section taken on the line $x-x$ of Fig. 1. Fig. 3 is a side elevation of the same, and Fig. 4 an inverted plan view.

The leading feature of my design consists in 15 four vertically-arranged plane surfaces whose upper and vertical edges terminate in beveled planes, each of the latter being of the same dimensions transversely, each having their ends determined by an angle. The lower 20 edge of the vertically-arranged plane surfaces aforesaid terminates in a beveled plane larger in its transverse dimensions than the others forming a part of the design. The horizontal plane surface forming the top of the bottle is 25 mounted with a tablet integral therewith, said tablet having each of its four corners formed by a double angle, thus giving it a plane surface. From the upper surface of the said tablet arises the neck of the bottle.

Similar letters and numerals refer to similar parts throughout the drawings, in which—

A represents the bottle, and *b* the vertically-arranged plane surfaces. The upper, lower, and vertical edges *2* terminate in the beveled surfaces *c* and *d*, the latter of which having their ends formed by the angles *3*. The lower beveled plane *d* is larger than those of *c*. The top of the bottle is provided with the tablet *e*, provided with the flat corners *4*. Said tablet is integral with the neck *f*.

It will be obvious that a bottle constructed in accordance with my design will present a brilliant object produced by prismatic effects of the different arranged beveled planes aforesaid.

What I claim is—

The design for a glass bottle substantially as herein shown and described.

In testimony that I claim the foregoing as my invention I have signed my name, in presence of two witnesses, this 19th day of April, 1895.

WILLIAM W. LOWREY.

Witnesses:

JOHN YSASI,
D. S. DOLBEAR.
